UNITED STATES PATENT OFFICE.

HENRY H. ELWELL, OF SOUTH NORWALK, CONNECTICUT.

DESIGN FOR A FOLDING DOOR-KEY.

Specification forming part of Design No. 3,942, dated March 29, 1870.

To all whom it may concern:

Be it known that I, HENRY H. ELWELL, of South Norwalk, in the county of Fairfield and State of Connecticut, have invented a new Design for Folding Door-Keys; and I do hereby declare the following, when taken in connection with the accompanying drawings and the letters of reference marked thereon, to be a full, clear, and exact description of the same, and which said drawings constitute part of this specification, and represent, in—

Figure 1, a side view, and in Fig. 2 an edge view.

This invention relates to a design for a folding key such as is formed from sheet metal, the object being, by the shape of the handle, to give to it the advantage of the bow, and also to inclose the bit of the key within the bow end of the handle.

A is the bit, formed upon a spindle, B, of sheet metal, and pivoted in the handle C at a, so as to turn therein like the blade of a knife. The handle is formed of two sides of sheet metal, and to the end D a shape is given similar to the bow of a common key, so as to give to the key by this shape the necessary leverage for turning, and also to entirely inclose the bit, as denoted in broken lines, Fig. 1.

I claim as my invention—

The design herein described for a handle for folding door-keys, consisting of two sides terminating in a rounded end, D, to inclose and cover the bit.

HENRY H. ELWELL.
